Patented Aug. 24, 1971

221,511

COMBINATION CORD AND ROPE WINDER

Leonard M. Dufault, 609 N. Naches Ave.,
Yakima, Wash. 98901

Filed May 14, 1970, Ser. No. 22,977

Term of patent 14 years

Int. Cl. D8—05

U.S. Cl. D8—220

FIG. 1 is a left rear perspective view of the combination cord and rope winder embodying my new design as viewed from the bottom;

FIG. 2 is a right front perspective view.

I claim:

The ornamental design for a combination cord and rope winder, substantially as shown.
